(57) **CLAIM**

The ornamental design for a case for camera, as shown and described.

DESCRIPTION

FIG. 1 is the front/right-side/top perspective view of a case for camera showing our new design;

FIG. 2 is the front elevational view thereof;

FIG. 3 is the rear elevational view thereof;

FIG. 4 is the left-side elevational view thereof;

FIG. 5 is the right-side elevational view thereof;

FIG. 6 is the top-side plan view thereof;

FIG. 7 is the bottom-side plan view thereof; and,

FIG. 8 is an isometric view of the case for camera in an alternate configuration, showing that the case slides on a camera.

The light, unevenly spaced broken lines shown in FIG. 8 represent environmental subject matter and form no part of the claimed design. All other dashed lines depict stitching.
